UNITED STATES PATENT OFFICE.

THOMAS V. HANDLOSER, OF NEW YORK, N. Y.

DESIGN FOR A FRAME FOR TRICYCLES.

SPECIFICATION forming part of Design No. 24,187, dated April 9, 1895.

Application filed November 30, 1894. Serial No. 530,484. Term of patent 14 years.

To all whom it may concern:

Be it known that I, THOMAS V. HANDLOSER, a citizen of the United States of America, residing at the city of New York, in the county 5 and State of New York, have invented and produced a new and original Design for Frames for Velocipedes, of which the following is a specification, reference being had to the accompanying drawings.

10 The characteristic feature of my design consists in the shape or configuration of the unitary design, as shown in the accompanying drawings.

Figure 1 represents a perspective view 15 taken from the front of the frame; and Fig. 2 is a similar view taken from the rear of the frame.

Numeral 1 designates the steering head of the frame located centrally between two handle-bar heads 2 and 3. 4 and 5 are two saddle supports terminating below in brackets 6—6, 20 and 7—7 are the two rear forks connected by bars 8—8 with the respective brackets 6—6 and laterally with each other by a rod 9. From

the brackets 6—6 extend braces 10—10 which 25 curve inwardly and upwardly and are connected to the steering head 1. From these braces project laterally curved branches 11—11 which connect respectively with the handle-bar heads 2 and 3. A substantially 30 straight rod 12 connects the braces laterally. From above the forked portion of the rear forks project braces 13—13 which curve inwardly and then outwardly and connect with the respective heads 2 and 3. A brace 14 projecting from the point of intersection of the two braces 13—13 connects with the steering-head 1. Short diagonal braces 15—15 may unite the rear forks and saddle supports.

What I claim as new is—

40 The design for a velocipede frame, substantially as herein shown and described.

In testimony whereof I affix my signature in the presence of two witnesses.

THOMAS V. HANDLOSER.

Witnesses:

J. H. FRANKFURTER,
GEORGE BRETEL.
